UNITED STATES PATENT OFFICE.

SIDNEY J. HOGAN, OF CHATTANOOGA, TENNESSEE.

FURNITURE-DRAWER GUIDE.

1,171,437.

Specification of Letters Patent. Patented Feb. 15, 1916.

Application filed August 17, 1915. Serial No. 45,902.

To all whom it may concern:

Be it known that I, SIDNEY J. HOGAN, a citizen of the United States, residing at Chattanooga, in the county of Hamilton and State of Tennessee, have invented a new and useful Improvement in Furniture-Drawer Guides, of which the following is a specification, reference being had to the accompanying drawing.

- 10 My improvement relates particularly to guiding means applied within a piece of furniture at the sides of the space occupied by a drawer when the latter is in the closed position, said guiding means being intended 15 to direct the drawer in a straight course when the drawer is being moved inward to or outward from its position of rest and to hold the drawer in proper position when at rest.
- 20 The object of the improvement is to provide such guiding means in a form adapted to cheap construction and to ready and precise adjustment to occupy positions adapted to limit lateral movement of the 25 drawer and to compel the inner end of the drawer to take such position as will bring the outer face of the outer end of the drawer into proper position relative to the front face of the furniture structure of which the 30 drawer forms a part. In regard to this latter feature, it is to be observed that if the inner end of the drawer is at the right or at the left of its true position, the outer face of the front end of the drawer will stand in 35 a slanting position, one corner being too far in or too far out.

In the accompanying drawings, Figure 1 is a horizontal, sectional view, portions being broken away, of a piece of furniture 40 containing a drawer with which my improvement is associated; Fig. 2 is a section on the line, 2-2, of Fig. 1, looking toward the left; Fig. 3 is a section on the line, 3-3, of Fig. 1, looking in the direction of the 45 arrow; Fig. 4 is a section on the line, 4-4, of Fig. 1, looking in the direction of the arrow; Fig. 5 is a section on the line, 5-5, of Fig. 3.

Referring to said drawings, A, A, are 50 four upright corner posts.

B is a rear wall piece extending from one rear corner post to the other and having its ends suitably joined to said corner posts, as by means of tongues and grooves, as shown 55 in the drawings.

C, C are two side wall pieces similarly

joined to the rear and the front corner posts.

D is a flat, horizontal bridge or sill piece placed between the two front corner posts 60 and secured thereto by mortising or otherwise.

E, E are rail or track pieces, one extending from each end of the bridge piece, D, rearward to the corresponding rear corner 65 post and being suitably secured, as by mortising into the rail piece and into the rear corner post. Said track pieces and said bridge piece constitute the support and track for the drawer, F. Said drawer and 70 other parts already described are of ordinary and well-known construction.

In each of the forward faces of the rear corner posts, A, A, is formed a groove or channel, G, standing oblique to the adjacent wall piece, C, the lower end of each groove being the nearer the adjacent side wall piece. On the rear face of each front corner post is a similar inclined groove or channel, H. Above each rail piece, E, is a 80 guide bar, I, having its rear end extending into the adjacent groove, G, and having its forward end extending into the adjacent groove, H. Each of said bars has its ends placed loosely in said grooves, so that either 85 end of the bar may be moved up or down; but each such end is preferably fitted closely enough to the groove to cause such frictional engagement as will temporarily hold a bar at any elevation to which it is intentionally put by a workman. In the form shown in the drawings, the face of each bar which is directed toward the space to be occupied by the drawer is made upright, each end of the bar being provided with a 95 tongue, J, which slants to conform to the slant of the grooves, G and H, and enters the adjacent of said grooves. This construction makes it possible to retain the upright position of the face of the bar which is 100 directed toward the space to be occupied by the drawer, regardless of the elevation at which said bar may stand. When said bars are in their lowermost positions, they stand at a certain distance from each other. If 105 they are now moved upward, they will approach each other; but the distance through which either of said bars moves toward the other is less than the upright distance through which said bar moves; for the 110 grooves, G and H, are between the vertical and an angle of 45 degrees. If either guide

bar is moved upward or downward equally at both ends, its horizontal, sidewise movement is the same at both ends. But either end of the bar may be moved sidewise independently by moving it upward or downward while the other end remains at rest.

When the piece of furniture is ready for the final fitting of the drawer, the two guide bars are set in any position that is thought to be approximately right. Then the rear end of the drawer is entered at the front and pushed back. If it becomes stuck, the guide bars are separated by driving one or both slightly downward. If the drawer again becomes stuck when it is pushed further rearward, the guide bars are further separated in the same manner. But if the space between the bars permits lateral movement of the drawer, the guide bars are moved upward. If such lateral movement is found possible at only one end of the drawer, the corresponding ends of the guide bars are raised. If it is found that the front face of the outer end of the drawer stands slantwise because the rear end of the drawer stands too far to the left or too far to the right, the rear end of one of the guide bars is moved up and the rear end of the other guide bar is moved down, so as to move the rear ends of the said guide bars sidewise in the direction necessary to move the rear end of the drawer into the position which will cause the front end of the drawer to assume a straight position. If the front end of the drawer does not fit closely against the front corner posts, lateral shifting or rattling of the drawer at said end may be prevented by moving the forward ends of the guide bars upward so as to make said bars bear closely against the forward portions of the side faces of the drawer. When the guide bars have been adjusted, as above described, until the drawer is held against lateral movement and to a true position and course, the guide bars, are, preferably, secured in any suitable manner, as by means of nails set to engage the corner posts and the adjacent ends of the guide bars, or by means of keys, K, seated in horizontal grooves, L, cut into the sides of the guide bars (see Fig. 5). Each such key may be driven toward and into the adjacent oblique channel, G, to engage by wedging or by entering the wood endwise. The nails and the keys may be withdrawn and reset, if adjustment of the guide bars is to be repeated. To facilitate engagement, the outer ends of the keys are turned sidewise to form arms, k.

Along the outer face of each side wall of the drawer, F, is a horizontal rib or bead, f, which makes contact with the corresponding outer corner post and the corresponding guide bar. The purpose of said bead is to reduce the area of frictional engagement

between the drawer on the one hand and said posts and guide bars on the other hand. It will be observed that the faces of the guide bars which are directed toward the drawer are of sufficient height to make engagement with the beads, f, although said bars are varied in elevation as above described.

In ordinary practice, fixed guide bars are used, in lieu of my adjustable guide bars, and said bars and the sides of the drawer planed and otherwise dressed until the drawer is assumed to be fitted. This method requires extra labor and the fitting can not be made as accurate as by the use of my adjustable bars. My construction is cheaper; my adjusting or fitting is cheaper; and my adjustment is more accurate.

I claim as my invention,

1. The combination of a drawer, a structure for receiving said drawer, and a pair of guide bars operatively related with said structure for the movement of said bars sidewise in paths inclined to a plane which is vertical and parallel to the drawer path, substantially as described.

2. The combination of a drawer and a structure for receiving said drawer and a pair of guide bars having their ends slideable up and down on said structure on inclined lines, substantially as described.

3. The combination with a drawer and a structure for receiving the drawer, of guide bars located at opposite sides for the space to be occupied by the drawer when the latter is in its position of rest and being held for inclined up and down movement, whereby said bars may be adjusted toward and from each other, substantially as described.

4. The combination with a drawer and a structure for receiving the drawer, of guide bars located at opposite sides of the space to be occupied by the drawer when the latter is in its position of rest and having upright opposing faces and being held for up and down movement on inclined ways, whereby said bars may be adjusted toward and from each other, substantially as described.

5. The combination with a drawer and a structure adapted to receive the drawer and having inclined grooves adjacent the space occupied by the corners of the drawer when the latter is in its position of rest, of guide bars having their ends resting in said grooves and movable up and down therein, whereby said bars may be adjusted toward and from each other, substantially as described.

6. The combination with a drawer and a structure adapted to receive the drawer and having inclined grooves adjacent the spaces occupied by the corners of the drawer when the latter is in its position of rest, of guide bars having upright opposing faces and having their ends resting in said grooves and

movable up and down therein, whereby said bars may be adjusted toward and from each other, substantially as described.

7. The combination with a drawer and a structure adapted to receive the drawer and having corner posts with inclined ways, of guide bars having their ends engaging said inclined ways, whereby said guide bars are held for up and down movement through which said bars are adjusted toward and from each other, substantially as described.

8. The combination of a drawer, a structure for receiving said drawer, and a pair of guide bars operatively related with said structure for the movement of said bars sidewise in paths inclined to a plane which is vertical and parallel to the drawer path, and members for securing said guide bars in chosen positions, substantially as described.

9. The combination of a drawer, a structure for receiving said drawer, and a pair of guide bars operatively related with said structure for the movement of said bars sidewise in paths inclined to a plane which is vertical and parallel to the drawer path, and keys having lateral arms and serving as means for securing said bars in chosen positions, substantially as described.

10. The combination with a drawer and a structure adapted to receive the drawer and having inclined grooves adjacent the space occupied by the corners of the drawer when the latter is in its position of rest, of guide bars having their ends resting in said grooves and movable up and down therein, whereby said bars may be adjusted toward and from each other, and members for securing said bars at chosen positions in said grooves, substantially as described.

11. The combination with a drawer and a structure adapted to receive the drawer and having inclined grooves adjacent the spaces occupied by the corners of the drawer when the latter is in its position of rest, of guide bars having grooves in their sides and having their ends resting in said inclined grooves and movable up and down therein, whereby said bars may be adjusted toward and from each other, and members in the grooves in said guide bars for securing said guide bars in chosen positions in said inclined grooves, substantially as described.

In testimony whereof I have signed my name this 2nd day of August, in the year one thousand nine hundred and fifteen.

SIDNEY J. HOGAN.
